United States Patent Office

Des. 185,741

Patented July 28, 1959

185,741

TELEVISION REMOTE CONTROL HANDSET

Bruce D. De Jager, Minneapolis, Minn.

Application January 9, 1959, Serial No. 54,124

Term of patent 14 years

(Cl. D26—14)

Fig. 1 is a perspective view of a television remote control handset showing my new design.

Fig. 2 is an end elevational view.

Fig. 3 is a side elevational view.

Fig. 4 is a plan view.

I claim:

The ornamental design for a television remote control handset, substantially as shown.
